UNITED STATES PATENT OFFICE.

THOMAS B. ATTERBURY, OF PITTSBURG, PENNSYLVANIA.

IMPROVED KILN FOR ANNEALING GLASS.

Specification forming part of Letters Patent No. 43,278, dated June 28, 1864.

To all whom it may concern:

Be it known that I, THOMAS B. ATTERBURY, of Pittsburg, in the county of Allegheny and State of Pennsylvania, have invented a new Kiln for Annealing Glassware; and I do hereby declare that the following is a full, clear, and exact description thereof, reference being had to the accompanying drawings, making a part of this specification, in which—

Figure 1 is a perspective view illustrating the operation of my invention. Fig. 2 is a top view of the kiln as seen by removing the circular arch. Fig. 3 is a front elevation of the kiln. Fig. 4 is a vertical transverse section, and Fig. 5 is a top view in detail showing the construction of the circular carriage and also the railway upon which this carriage moves.

Similar letters of reference indicate corresponding parts in the several figures.

My invention consists in a leer or kiln for annealing glassware, which is so constructed that the ware will be subjected to a uniform degree of heat in passing through one portion of said kiln, and then gradually cooled in leaving said heated portion, as will be hereinafter described.

My invention also consists in a novel construction and arrangement of the parts, substantially as will be hereinafter described.

To enable others skilled in the art to make and use my invention, I will describe its construction and operation.

In the accompanying drawings, A represents a circular platform or carriage, which is made up of flanged segmental sections having their tapering edges so formed and put together as to give the carriage a level upper surface. This circular carriage is mounted upon flanged wheels, a a, the axles of which are arranged in lines radiating from the center, around which the carriage revolves, and these wheels travel upon rails b b, which are composed of sections, as shown in Fig. 5, secured down upon a circular foundation of masonry in such manner as to provide against the springing up of the rails in consequence of the extremes of temperature to which they are subjected. The ends of the rails b b are prevented from being thrust out of place laterally by wedging and notching these ends and fitting the sections together as represented in Fig. 5.

The foundation upon which the carriage A

revolves is represented by B, Figs. 1, 2, and 3, and it is provided with one or more chambers, C, which form ash-pits for the fire-places. In the present instance only one of these chambers is made, as only one fire is used; but it may be found desirable in very large leers or tempering-kilns to use a number of fires arranged side by side at and near the point where the glassware is introduced into the annealing-passage. When the traveling carriage is properly constructed and mounted upon its rails b b, an arch D is built over it extending from the closed end D' around to the opening, which is shown in Figs. 1 and 3, and which is intended to allow of the ware being removed from the carriage A. The highest points of the arch D are at D' and at its opposite termination, the lowest point being where I have represented a chimney, E.

By constructing the arched chamber, through which the ware is conveyed, as above described, the ware will be subjected to a uniform heat in passing through one portion of the leer, after which the ware will be gradually cooled by passing through a chamber which gradually increases in size from the locality of the chimney to the delivery-opening.

By constructing the annealing-chamber as above described—*i. e.*, with an arch flaring from a certain point toward both ends—there will be a draft from the fire-chamber at d, passing toward the chimney E, and also another slight draft in an opposite direction through the opposite end of the arch. I thus obtain in a single passage two drafts, one being heated air and the other cool air, one heating the ware and the other gradually cooling and annealing it, so that the annealed work is delivered at the opposite end of the arch to that in which the fire is placed, and at or near a point where the work is introduced into the annealing-chamber. G represents the ware-door through which the ware to be annealed is passed into the annealing-chamber. This is the hottest point, it being nearest the fire or fires, as the case may be.

When that portion of the carriage A opposite said door is filled with ware the carriage is moved a short distance by means of a chain which is hooked to the exposed portion of the carriage and wound around the windlass g by means of the spur-wheels and crank, as represented in Fig. 1. In this way the car-

riage is rotated and filled, and as fast as the annealed ware emerges from the arch at the delivery-opening it is removed from the carriage. Instead of employing the chain and windlass to move the carriage A, it may be moved by means of a circular rack and a driving pinion applied to it, or in any other convenient manner.

I am aware that a circularly-moving pan covered by an arch is not new in connection with a glass-annealing furnace. Therefore I do not claim such as my invention; but

What I claim as new is—

1. A leer or kiln for annealing glassware, constructed with a depressed arch having inlets and outlets for the glass, combined with

the endless closed carriage and circular railway, substantially as described.

2. Depressing the circular arch at or near the chimney E, substantially in the manner and for the purposes described.

3. A leer for annealing glassware, which is so constructed that the ware is subjected to an intense but nearly uniform heating process in passing through one portion of the annealing chamber of the leer, and is then subjected to a gradually cooling process in leaving the point where the chimney-flue is located, substantially as described.
